Berlin, and Georg Gaidies, Berlin-Pankow,
Germany, assignors to General Electric Com-
pany, a corporation of New York

Application April 4, 1932, Serial No. 603,168
In Germany April 15, 1931

4 Claims. (Cl. 176—124)

The present invention relates to gaseous electric discharge devices generally and more particularly the invention relates to methods and means for facilitating the starting into operation of such devices.

It is now known in the art that the starting of gaseous electric discharge devices is facilitated by the arrangement of an auxiliary electrode in the region of the main discharge supporting electrode in such manner that an electric discharge takes place between them which ionizes the gaseous filling to facilitate the starting of the main discharge in the device. The object of the present invention is to make the starting of gaseous electric discharge devices equipped with auxiliary electrodes more positive and quicker than has been the case heretofore. Still further objects and advantages attaching to the invention and to its use and operation will be apparent to those skilled in the art from the following particular description and from the appended claims.

In accordance with this object the invention comprises, in one embodiment thereof, one or more electrically conducting members in the container of an electric discharge device extending along the discharge path between the main discharge supporting electrodes. One end of each of said members is at a distance from one of said electrodes equal to, or, preferably, less than the striking distance of the potential applied to said device. The striking distance is here defined as the maximum distance at which an electric discharge will strike between two discharge supporting bodies at a given potential. Each of said members is connected through a resistance to the main discharge supporting electrode opposite that to which it is in close proximity; the electrically conducting members thus act as auxiliary electrodes. Said members are arranged in physically parallel relation with respect to each other and are separated a distance less than the striking distance of the potential applied thereto. When current of suitable potential is applied to the terminals of the device three discharges are struck one between each of the main discharge supporting electrodes and the end of the auxiliary electrode in close proximity thereto and one between the auxiliary electrodes themselves so that a multiplicity of discharges occur along the length of the discharge path between the main discharge supporting electrodes to cause a quick and heavy ionization of the gaseous filling in the container

of the device and the device is started into operation positively and quickly.

In another embodiment of the invention the electrical conductors extend only part way along the discharge path and another electrical conductor is arranged parallel thereto and at a distance therefrom less than the striking distance of the potential applied to said first mentioned electrical conductors. The ends of said second named conductor are at a like distance from said electrodes. Said last named electrical conductor is not connected into the circuit. In this embodiment four auxiliary discharges are struck along the discharge path between said main discharge supporting electrodes, one between each of said main electrodes and said second named discharge electrical conductor and one between each of said first named conductors and said second named conductor. This embodiment of the invention is used with greater potential than the embodiment described above.

In the drawing accompanying and forming part of this specification two embodiments of the invention are illustrated in which

Fig. 1 is a side elevational view of one embodiment of the new and novel gaseous electric discharge device, the circuit therefore being shown schematically and

Fig. 2 is a similar view of another embodiment of the invention.

Like numbers denote like parts in both figures.

Referring to Fig. 1 the new and novel electric discharge device comprises a container 1 filled with the usual discharge conducting atmosphere such as gases, gas mixtures, vapors, or a gas vapor mixture, said atmosphere is, for example, neon. Electrodes 3 are provided at each end of said container 1, and the in-leads 5 thereof are sealed into pinch-parts 4 of stems 2. Said in-leads 5 are connected to the terminals 7 of an alternating current source of 110 or 220 volts usual in commerce, by leads 6. The usual ballast resistance 8 is connected into one of the leads 6.

Two conducting members 9 and 10 are sealed in said pinch parts 4 at opposite ends of the container 1, said members extend along the discharge path between said electrodes 3 and the interior end of each of said members 9 and 10 are at a distance from one of said electrodes 3 less than the striking distance of the potential applied to the device. Said members 9 and 10 are arranged in parallel positions in said container 1 and the distance between them is less than the striking distance of the potential applied thereto. Each of said conducting members 9 and 10 is con-

nected with one of the electrodes 3 through a resistance 11 or 12 respectively. Said members 9 and 10 are supported in said container 1 by glass beads 13 fused to said conductors 9 and 10 and 5 to support wires 14, said support wires 14 being fused into the glass walls of said container 1.

Upon the application of current to the terminals of the device three glow discharges are struck along the main discharge path, one between each of the electrodes 3 and the end of the respective conducting members 9 or 10 in close proximity thereto and one between the electrical conducting members 9 and 10. The main discharge path is then occupied by a plurality of glow 10 discharges which cause a prolific emission of electrons and ions to ionize the gaseous filling. When the gaseous filling is sufficiently ionized, which takes place in a fraction of a minute, the main arc discharge is struck between the main electrodes 3.

The main electrodes 3, when desired, are of the self-heating sintered, pressed, mixture of electron emitting material and high melting point metal type disclosed in co-pending application 25 Serial No. 377,044, filed July 9, 1929, the inventors being Marcello Pirani and Hans Ewest. A special heating means is used when desired. Or, when desired, said electrodes are of the type disclosed in co-pending application Serial No. 447,051, filed 30 April 24, 1930, the inventors being Georg Gaidies and Marcello Pirani.

The embodiment of the invention shown in Fig. 2 is in all respects similar to that shown in Fig. 1 except that conductors 9 and 10 are in linear 35 relation, the ends thereof being separated a greater distance than the striking distance of the potential applied thereto and a third conducting member 16 is arranged in said container 1 parallel to said members 9 and 10 and at a distance less 40 than the striking distance of the potential applied to said conductors 9 and 10. The respective ends of conductor 16 are at a distance from said electrodes 3 less than the striking distance of the potential applied thereto. Said conducting member 45 16 is not connected into the circuit. Said members 9, 10 and 16 are supported in said container 1 by glass beads 17 and metal supports 18 and the ends of said member 16 overlap the ends of said members 9 and 10.

When current is applied to the terminals of the device four glow discharges are struck, one between each of the members 9 and 10 and the member 16, and one between each of the respective ends of said member 16 and each of the electrodes 3. Thus in this embodiment the main discharge path is more quickly and heavily ionized than in the embodiment shown in Fig. 1 due to the greater number of discharges and the electric discharge device is started into operation 55 with greater facility. Further, due to the striking of four glow discharges during the starting operation a higher potential may be used in conjunction with this embodiment of the invention, for example, an operating potential of 300 volts is 60 use when desired. When desired a still higher voltage than 300 volts is applied to the electric discharge device and in this case member 16 is 65

divided in such manner that a glow discharge takes place between the ends thereof opposite to those ends in close proximity to electrodes 3.

While we have shown and described particular 5 embodiments of our invention it will be understood of course that various substitutions, omissions and changes, in the forms and details of the device illustrated and in its use and operation may be made by those skilled in the art without departing from the broad spirit and scope of the 10 invention, for example, said members 9, 10 and 16, are, when desired, coated with electron emitting material.

What we claim as new and desire to secure by Letters Patent of the United States is:—

1. An electric discharge device comprising a container, electrodes sealed therein, a gaseous atmosphere therein, and at least one continuous electrically conducting member extending along the discharge path between said electrodes and coextensive with said path, said member being connected through a resistance with one of said electrodes, the end of said member being located at a distance from the electrode opposite that to which is connected less than the striking distance of the potential applied to said device.

2. An electric discharge device comprising a container, electrodes sealed therein, a gaseous atmosphere therein, and a plurality of electrically conducting members extending along the discharge path between said electrodes and in parallel positions, each of said members being connected through a resistance with one of said electrodes, one end of each of said members being adjacent one of said electrodes opposite that to which said member is connected, the distance between said ends and said electrodes and the distance between said members being less than the striking distance of the potential applied to said device.

3. An electric discharge device comprising a container, electrodes sealed therein, a gaseous atmosphere therein, and a plurality of electrically conducting members extending along the discharge path between said electrodes, two of said members being mounted substantially in the same line and one of said members being parallel thereto, each of said first named members being connected through a resistance with one of said electrodes, the distance between said first named members and said second named member, and the distance between the respective ends of said second named member and said electrodes being less than the striking distance of the potential applied to said device.

4. An electric discharge device comprising a container, main discharge supporting electrodes sealed therein, a gaseous atmosphere sealed therein, and auxiliary electrodes sealed therein, said auxiliary electrodes extending along the discharge path between said main discharge supporting electrodes, the ends of said auxiliary electrodes overlapping along said path.
